UNITED STATES PATENT OFFICE.

DANIEL SCANLAN, OF ST. LOUIS, MISSOURI, ASSIGNOR OF ONE-THIRD TO HARRY E. HAEDER, OF ST. LOUIS, MISSOURI.

ROPE-MACHINE.

1,150,151.

Specification of Letters Patent. Patented Aug. 17, 1915.

Application filed March 22, 1912. Serial No. 685,628.

To all whom it may concern:

Be it known that I, DANIEL SCANLAN, a citizen of the United States, residing in the city of St. Louis and State of Missouri, have 5 invented a new and useful Rope-Machine, of which the following is a specification.

This invention relates to improvements in rope machines.

In certain machines it is useful, and indeed often necessary that the machine be automatically stopped when the feeding of material being operated upon to the machine for any reason is interrupted. Especially is this true in a stranding machine used in 15 winding rope. When one strand of wire or other material fed to the machine in rope winding becomes broken, if the machine continues to operate a defective product will result. Therefore the machine should be 20 brought to an immediate stop, when a wire or cord breaks.

An object of the present invention is to provide a means in combination with stranding or rope winding machines, of automatic 25 mechanism which is actuated upon the interruption of the normal feed of the rope making material effectively to stop the operation of the machine so as to prevent the production of defective rope with broken wires or 30 cords, and to enable the operator to make such repairs as are necessary to permit the continuous feed of the rope material to the winding head of the machine and which mechanism will also be operable to stop the 35 machine, should any of the wires or cords become loose so as to produce rope where each of the wires or cords have a uniform tension.

To this and other obvious ends, I have de- 40 signed, combined and arranged the several coöoperating parts hereinafter shown, illustrated and embraced within the scope of the appended claims.

In the drawings, in which like characters 45 of reference indicate like parts throughout the several views—Figure 1 is a side elevation of the principal operating parts of a stranding machine showing a preferred manner of embodying my invention therein. 50 Fig. 2 is a sectional view on the line 2—2 of Fig. 1, the operating-fluid passages being omitted. Fig. 3 is a sectional view on the

line 3—3 of Fig. 2. Fig. 4 is a detail sectional view showing one of the pins for tripping the release mechanism, held in normal 55 position. Fig. 5 is a similar view showing one of the tripping pins released after a wire has been broken. Fig. 6 is a sectional view on the line 6—6 of Fig. 4. Fig. 7 is a plan view of the tripping and valve operating 60 mechanism, viewed from a line such as 7—7 of Fig. 2. Fig. 8 is a detail sectional view on the line 8—8 of Fig. 7, showing the latch device for holding the mechanism in normal position for operation of the machine, 65 said latch device being automatically tripped in case of accident as hereinafter described, to cause the machine to stop. Fig. 9 is a sectional view through the valve which controls the operation of the machine. Fig. 10 70 is a transverse sectional view through the valve in adjustment to stop the machine, and Fig. 11 is a similar view showing the position of the valve when the machine is in normal operation. 75

In the drawings I have illustrated my invention embodied in a stranding machine for rope winding. The main longitudinal shaft 1 of the machine, is driven by a main drive pulley 2 which receives power from any 80 suitable source to which it is connected by a belt 3, or other equivalent connection; the drive pulley 2 is loose on the shaft 1 and is arranged to be operatively connected therewith by means of a suitable clutch mechanism 85 which comprises a collar 4, which is slideable longitudinally on the shaft 1; said collar 4 being actuated by a lever 5 pivoted to a suitable support 6. A band 7 encircles the hub of the pulley 2 and is tightened and 90 released as the collar 4 is moved by the lever 5 through the toggle links 8 and the levers 9, as will be readily understood. The lever 5 is actuated by a fluid motor A, which comprises a cylinder 10 in which is operatively 95 mounted a piston, carrying a piston rod 10^a, which is connected to the lower end of the lever 5. As the lever 5 is actuated to the left (Fig. 1), the band 7 will be tightened about the hub of the pulley 2, thereby setting the clutch mechanism so that the shaft 1 will be driven as the pulley 2 is actuated. A fluid passage 11 enters the cylinder 10 at one end thereof, and a second fluid pas-

sage 12 enters the opposite end; it will be understood that as pressure is admitted through one or the passages 11 or 12, and the pressure released in the other of said passages, that the piston mounted in the cylinder 10 will be driven to and fro in the cylinder, thereby actuating the lever 5, effectively to control the clutch mechanism. The shaft 1 has rigidly fixed thereto a band wheel 13 which is encircled by a band 14 the ends of which are secured to one arm of the bell crank lever 15, said bell crank lever 15 being pivoted to a suitable support 16. A second fluid motor B is provided for actuating said lever 15 and thereby controlling the band 14 encircling the wheel 13, which parts constitute a band brake for releasing and locking the shaft 1. The motor B comprises a cylinder 17 in which is operatively mounted a piston which carries a piston rod 18, which is pivoted to one arm of the lever 15. A spring 19, encircles the piston rod 18 and holds the brake mechanism normally in released adjustment. As fluid pressure is admitted through the passage 20, the piston mounted in the cylinder 17 is driven to the right (Fig. 1), thereby tightening the band 14 about the band wheel 13, effectively to lock the shaft 1.

30 The pressure in the passages 11, 12 and 20 is normally controlled by means of a valve C which is interposed between said passages and the main supply passage 21, which communicates with any suitable 35 source of fluid pressure supply. In starting the operation of the machine the clutch is set, by communicating the passages 21 and 11 through the valve C, which throws the piston in the cylinder 10 to the left (Fig. 40 1), in which position it remains until pressure is introduced into the passage 12.

In machines of the type in which I have 45 illustrated the embodiment of my invention, the shaft 1 carries a series of rings 22, (only one of which is illustrated for the purpose of convenience), each of which rings is supported by supporting roller 23 mounted in the base D of the machine. The wires or fiber cords are carried forward from rings 50 and are passed through slots in the rings 22 arranged adjacent to the peripheries thereof, at equidistant points on their circumferences and are fed forward into the winding head E.

55 The mechanism for automatically controlling the motors A and B constitutes a part of my present invention and as illustrated in the embodiment shown comprises, a plate 24 which is provided with a series of equidistant slots 25 arranged in its periphery; the number of slots being the same as the number of wires or cords being fed to the winding head E. The plate 24 is rigid on the shaft 1 and is positioned intermediate the forward ring and the winding head E, as

clearly appears by reference to Fig. 1 of the drawings. The twisting head E may be of any of the usual types and it will be understood that said twisting head is adapted to wind or twist the cords or wires to form a 70 rope. The cords or wires are drawn from the reels or bobbins and are guided or fed to the twisting head by the plates 24 and rollers 31 and 32. Each of the slots 25 has a corresponding radial bore 26 in which is mounted a tripping pin 27, said pin 27 being slidable radially of the plate 24 and the movement of which is limited by a cotter pin 28 co-operating in a slot 29 formed in the plate 24. At either side of the plate 24 are flanges 30 which carry a series of roller supports 31 in which are operatively mounted rollers 32, the arrangement being such that the inner series of rollers 32 extend slightly beyond the periphery of the plate 24 and the outer series of rollers 32 being slightly within the periphery of said plate 24. As the wires or cords 33 are drawn forward they are passed under the inner rollers 32 and through the slots 25 and over the outer rollers 32, to the twisting head E, and in normal feeding are held taut, thereby retaining the pins 27 within the periphery of the plate 24 in the manner illustrated in Fig. 4. Should any one of the wires or cords as they are being fed to the twisting head E, become broken, the pin 27 held in place thereby, would be released and as the plate 24 is revolving, the pin would be thrown by centrifugal force beyond the periphery of the plate to a position shown in Fig. 5 and come into the path of the end of lever 34 which is pivoted at its lower end in a suitable lug 35 on the upper face of the stand 36. The lever 34 is normally in vertical position and carries at one side thereof, a roller 37 which normally bears against the upper face of the lever 38, one end of which lever 38 is pivoted in the lug 39 mounted on the upper face of the stand 36. The lever 38 normally rests in a horizontal position and is provided with a notch 40 adjacent to its free end, which constitutes a latch for one end of the lever 41; said lever 41 having connected to its opposite end, one end of a tractile spring 42, which spring is secured to the upper face of the stand 36 in such a manner that when the forward end of the lever 41 is released it will be actuated to the position shown in dotted lines in Fig. 7. The lever 38 operates in a guide 38a and it will be apparent that as the lever 34 is thrown to the oblique position, shown in Fig. 2 in dotted line, by a tripping pin 27, that the free end of the lever 38 will be depressed sufficiently to unlatch the lever 41. The lever 41 is secured to the upper part of the valve plug 43; said plug 43 being operatively mounted in the valve case 44. The actuating fluid supply passage 45 enters the 130

- valve case 44 and the outlet passage 46 which communicates with the passage 20, and the outlet passage 47 which communicates with the passage 12, lead from the valve case 44.
- 5 The valve plug 43 is provided with a three-way passage 48 so that when the valve plug 43 is thrown to the position shown in Fig. 10, by the lever 41, coöperating with the spring 42, the passages 12 and 20 will be 10 immediately communicated with the pressure supply passage 45. In the normal adjustment of the valve, as shown in Fig. 11, the supply passage 45 is closed so that there will be no pressure through the valve introduced into the passages 12 and 20. It will be readily understood that when the valve is opened that by the lever 41, pressure will be admitted to the passages 12 and 20 effectively to operate the fluid motors A and B 15 thereby releasing the clutch mechanism and applying the brake, immediately stopping the operation of the machine.

I am aware that several minor changes in details of arrangement and construction may 20 be made without departing from the spirit and scope of the invention, I do not limit myself, therefore, to details, but

What I claim and desire to secure by Letters Patent is—

- 30 1. In a machine of the character mentioned, the combination with mechanism for twisting wires to form a rope, of a clutch device, a device for positively stopping the operation of said twisting mechanism, independent motors for actuating said devices, 35 tripping pins arranged to be supported by the wires being fed to said twisting mechanism, a lever automatically engaged by any one of said tripping pins after the corresponding supporting wire breaks, and means controlled by said lever for causing said motors to operate effectively to cause the clutch to 40 be released and said stopping device to be set effectively to stop the operation of said machine, substantially as specified.

- 45 2. In a machine of the character mentioned, the combination with mechanism for twisting wires to form a rope, and means for driving said twisting mechanism, of mechanism for stopping the operation of said twisting mechanism comprising a series of tripping pins arranged to be supported by the wires when said wires are being normally fed to said twisting mechanism, a lever arranged to be automatically engaged by any one of said tripping pins when the normal feeding of any one of the wires becomes interrupted, a latch device controlled by said lever, a clutch, a 50 brake, fluid motors for controlling said clutch and said brake, and a device for controlling said fluid motors arranged to operate when said latch is released when any one of said tripping pins engages said lever, substantially as specified.

3. In a machine of the character mentioned, the combination with a main drive shaft and a power pulley loosely mounted thereon, of a clutch interposed between said shaft and pulley, a plate carried by said shaft, a series of tripping pins arranged in said plate which are supported by the wires or threads when said wires or threads are being normally fed, a lever arranged to be automatically engaged by any one of the tripping pins when the feed of any one of the wires or threads becomes interrupted, a latch device controlled by said lever, a fluid motor for operating said clutch, and a device for controlling said fluid motor which operates when said latch is released as aforesaid, substantially as specified.

4. In a stranding machine, the combination with a driving shaft, means for driving the same, a clutch between said shaft and said driving means, a brake for locking said shaft, a plate carried by said shaft provided with slots in its periphery, and radial bores extending inwardly from said slots, movable pins in said bores arranged to be held within the periphery of said plate by the material being operated upon, and mechanism for actuating said clutch and said brake when the supporting material for said pins is released, substantially as specified.

95 5. In a rope machine, the combination with a twisting head for twisting wires fed thereto, driving means for actuating said machine, means for operatively connecting and disconnecting said driving means with the machine, a brake device, a fluid motor for actuating said means for operatively connecting and disconnecting said driving means, and an independent fluid motor for actuating said brake device, of automatic 100 devices independently controlled by the wires being fed to the twisting head of the machine for causing the operation of said fluid motors effectively to simultaneously set said brake and to disconnect said driving means when the normal feeding of any one of said wires becomes interrupted, substantially as specified.

110 6. In a rope machine, the combination with mechanism for twisting wires to form a rope, power mechanism, a clutch for operatively connecting and disconnecting said power mechanism with the machine, brake mechanism, and fluid motors arranged to 115 actuate said brake mechanism and said clutch mechanism, of automatic devices each under the control of one of the wires being fed to said twisting mechanism adapted to cause the setting of said brake mechanism and to disconnect said clutch mechanism whenever the normal feeding of any one of the wires becomes interrupted, substantially as specified.

120 7. In a machine of the character described, the combination with a drive shaft, 125

rope twisting mechanism driven by said shaft, a pulley loosely mounted upon said shaft for driving said shaft, releasable mechanism for locking said pulley in engagement with said shaft, and an actuator for releasing said last-named mechanism to enable said pulley to turn independently of said shaft, of a brake for stopping said shaft when said pulley is released from said shaft, automatic mechanism for effecting the release of said pulley from said shaft as an incident to the breaking of any of the wires being twisted, and automatic means for setting said brake concurrently with the release of said pulley, effectively to stop said shaft, substantially as specified.

8. In a rope machine, the combination with mechanism for twisting wire to form a rope, an actuator for said twisting mechanism, a revoluble support provided with guide ways for the wires passing to said twisting mechanism, and a device for locking said mechanism against operation, of independent automatically controlled mechanisms each including a motor for controlling said actuator and said device, elements mounted in said revoluble support under control of the separate wires moving to said twisting mechanism for controlling the operation of said motors to release said actuator and to set the lock device, and a separate device for controlling said motors to re-engage said actuator and to release said lock device.

35. 9. In a rope machine, the combination with a main operating shaft, a twisting head adapted to twist wires to form a rope, mechanism adapted to guide said wires to said twisting head, a power pulley loosely mounted on said shaft, clutch mechanism for connecting and disconnecting said shaft and said power pulley, brake mechanism for said shaft, fluid motors arranged to actuate said brake mechanism and said clutch mechanism, of automatic devices carried by said shaft arranged to operate incidentally to the interruption of the normal feeding of any one of said wires effectively to cause said motors to release said clutch and to apply said brake, and means for resetting said clutch and releasing said brake, substantially as specified.

10. In a rope machine, the combination with mechanism for twisting wires to form a rope, an actuator for said twisting mechanism, a revoluble support under control of said actuator, guides on said support for the wires passing to said twisting mechanism, and a brake for stopping said mechanism, of independent automatically controlled mechanisms including in each mechanism a motor for controlling said actuator and said brake, and elements mounted in said revoluble support and controlled by the separate wires moving to said twisting mechanism for con-

trolling the operation of said motors to release said actuator and to stop said twisting mechanism and said revoluble support.

11. In a rope machine, the combination with a main operating shaft, a twisting head driven by said shaft, power devices for driving said shaft, a brake for said shaft, a motor for operating said brake, a motor for operating said power devices, devices arranged to be supported in inoperative position by the separate wires moving to said twisting head, of mechanism for causing said motors to operate to set said brake and to disconnect said power device when the normal feeding of any one of said wires becomes interrupted, substantially as specified.

12. In a rope machine, the combination with mechanism for twisting wires to form a rope and means for driving said mechanism, mechanism for stopping the operation of said twisting mechanism, comprising a plurality of automatic devices under the control of the separate wires, said devices arranged to be supported by said separate wires when the same are being normally fed to the twisting mechanism, a clutch device, a brake, fluid motors for controlling said clutch device and said brake, and a device for controlling said fluid motors arranged to operate when any one of said devices under the control of said wires moves from its normal position incidentally to the interruption of the normal movement of said wires to said twisting mechanism, substantially as specified.

13. In a rope machine, the combination with a drive shaft, a twisting head adapted to twist wires to form a rope driven by said drive shaft, a revoluble support carried by said drive shaft provided with guide ways for guiding the wires being fed to said twisting head, power mechanism for actuating said drive shaft, a connection for operatively connecting and disconnecting the power mechanism and the drive shaft, and brake mechanism for said drive shaft, of independently controlled mechanisms including in each mechanism a motor for controlling said power connection and said brake, elements mounted in said revoluble support under the control of the separate wires moving through said guide ways to said twisting head operable effectively to cause said motors to operate to release the power connection and to set said brake when the normal movement of any one of said wires becomes interrupted, and means operable effectively to cause said motors to operate to release said brake and re-set the power connections, substantially as specified.

14. In a rope machine, the combination with mechanism for guiding wires, mechanism for twisting said wires to form a rope, power mechanism, a clutch for operatively connecting and disconnecting said power

- mechanism with the machine, brake mechanism, and fluid motors arranged to actuate said brake mechanism and said clutch mechanism, of devices each under the control of 5 the separate wires being guided by said guiding mechanism adapted to cause the setting of said brake mechanism and to disconnect said clutch mechanism whenever the normal movement to said twisting mechanism of any one of said wires becomes interrupted, and means for re-setting said clutch and releasing said brake, substantially as specified.
15. In a rope machine, the combination with a twisting head, a shaft for driving said twisting head, a revoluble support mounted on said shaft provided with guide ways for the separate wires moving to said twisting head, and a brake device for said 20 shaft, of a plurality of elements in said support normally retained in inoperative position by the wires moving to said twisting head through the guide ways in said support, mechanism including a prime mover 25 for actuating said brake, driving mechanism for said drive shaft, mechanism including a prime mover for connecting and disconnecting said shaft and said power mechanism, and means adapted to be actuated by 30 one of the elements in said support when the normal movement of any one of the wires to the twisting head becomes interrupted whereby said prime movers are operated to set said brake and to release said power 35 mechanism from said drive shaft.
16. In a rope machine, the combination with a twisting head, a shaft for driving said twisting head, a revoluble support mounted on said shaft provided with guide 40 ways for the separate wires moving to said twisting head, and a brake device for said shaft, of a plurality of elements in said support normally retained in inoperative position by the wires moving to said twisting 45 head through the guide ways in said support, mechanism including a prime mover for actuating said brake, driving mechanism for said drive shaft, mechanism including a prime mover for connecting and disconnecting said shaft and said power mechanism, means adapted to be actuated by one of the 50 elements in said support whereby the prime movers in said mechanisms are caused to operate when the normal movement of any 55 one of the wires to the twisting head becomes interrupted effectively to set said brake and to release the power mechanism from said drive shaft, and a device operable to reverse the movement of said prime movers whereby the brake is released and the power mechanism connected with the drive shaft.
17. In a rope machine, the combination with a main drive shaft, twisting mechanism 60 driven by said shaft, a support pro-
- vided with guide ways for the wires moving to said twisting mechanism, and elements in said support under the control of the separate wires, of power mechanism for said drive shaft, a motor with associated mechanism for connecting and disconnecting said drive shaft and said power mechanism, a brake, a motor with associated mechanism for controlling said brake, and a device, adapted to be actuated by any one of said elements in said support when the normal feed of its associated wire becomes interrupted, operable effectively to cause said motors to operate to set said brake and disconnect said power mechanism from said drive shaft.
18. In a rope machine, the combination with a main drive shaft, twisting mechanism driven by said shaft, a support provided with guide ways for the wires moving to said twisting mechanism, and elements in said support under the control of the separate wires, of power mechanism for said drive shaft, a motor with associated mechanism for connecting and disconnecting said drive shaft and said power mechanism, a 70 brake, a motor with associated mechanism for controlling said brake, and a device, adapted to be actuated by any one of said elements in said support when the normal feed of its associated wire becomes interrupted, operable effectively to cause said motors to operate to set said brake and disconnect said power mechanism from said drive shaft.
19. In a rope machine, the combination with mechanism for guiding wires, a twisting head, power mechanism, a brake, a motor for controlling said brake, and a motor for controlling said power mechanism, of automatic devices each under the control of the separate wires moving to said twisting head operable effectively to cause the said motors to operate to set said brake and disconnect said power mechanism when the normal feed of any one of the wires becomes interrupted, and an independent device operable effectively to reverse the operation of said motors whereby the brake is released and the power mechanism reconnected.
20. In a rope machine, the combination with a drive shaft, a twisting head, a support provided with guide ways for the wire moving to said twisting head, devices movable in said support retained in normal position by the separate wires seated in said guide ways, power mechanism, a motor with associated mechanism for connecting and disconnecting said power mechanism and said drive shaft, a device adapted to be actuated by any one of said movable devices

in said support when the same is released by its associated wire whereby said motor is actuated effectively to disconnect said power mechanism from said drive shaft, and a 5 separate device for causing said motor to operate to re-connect said power mechanism and said power shaft.

In witness whereof, I have signed this specification in the presence of two subscribing witnesses.
